UNITED STATES PATENT OFFICE.

AUGUSTUS H. STOWELL, OF SPOKANE, WASHINGTON.

WALL STRUCTURE.

1,397,708.

Specification of Letters Patent. Patented Nov. 22, 1921.

Application filed June 7, 1920. Serial No. 386,988.

To all whom it may concern:

Be it known that I, AUGUSTUS H. STOWELL, a citizen of the United States, residing at Spokane, in Spokane county, and State of Washington, have invented certain new and useful Improvements in Wall Structures, of which the following is a specification.

The present invention relates to an improved wall structure made up of tiling and designed especially for the lining of flumes, ditches, &c., in irrigation operations, the primary object of the invention being the provision of a wall or lining for the ditch that is durable, strong, comparatively cheap in cost of production, and which may be built with comparative ease and quickness, thus reducing the factors of time and labor in the construction work.

With the above and other objects in view the invention consists in certain novel combinations and arrangements of tiles as will be hereinafter more fully set forth and claimed.

In the accompanying drawings I have illustrated one complete example of my invention physically embodied as an irrigation flume, in which the parts are combined and arranged according to the best mode I have thus far devised for the practical application of the principles of my invention.

Figure 1 is a view showing a portion of the lining of an irrigation flume, embodying the invention.

Fig. 2 is a transverse sectional view of the lining or wall.

Fig. 3 is a perspective view of one of the tiles, inverted.

In the construction of an irrigation flume, a portion of which is illustrated in Fig. 1 as L, the ditch of which this lining forms a part, is semicircular in cross section, and the tiles 1 may be laid directly on the curved surface of the ditch, or if desired a bedding of cement may first be applied to the concave walls of the ditch and the tiles laid therein.

The tiles are of rectangular shape and curved in cross section to conform to the curved walls of the ditch in which they are to be laid.

At one of its sides each tile is provided with a longitudinally extending dovetail bead 2 projecting below the outer surface of the tile and forming one of the walls of a

recess 3 at the lower face of the tile, while the opposite side or edge of the tile is fashioned with an oppositely projecting key flange 4 which forms a groove 5 opening up to the upper or inner face of the tile. Thus the bead 2 and the flange 4 project in opposite directions from the outer face of the tile, and the bead 2 on the outer face of the tile as it is built into the wall projects into the inwardly opening groove 5 of the adjoining tile forming a dovetail joint, and the edge of the flange 4 fits against the under face of the tile at the inner side of the bead, as shown in Fig. 2.

The grooves 5 of the aligned tiles form continuous channels in the wall and the beads 2 form continuous tongues to fit in these channels extending the full length of the wall or lining L.

At one end of the tile a transverse bead 6 is fashioned, similar to the bead 2 but terminating a short distance from bead 2 in order to afford a continuous channel and this bead also projects outwardly from the tile when the latter is in place in the lining or wall, the bead terminating or merging at one side of the tile into the flange 4. At the other end of the tile a flange 7 is fashioned and forms a groove 8 at the end of the tile, the flange depending at its base from the lower or outer face of the tile, with its edge projecting upwardly or inwardly, and as seen in Fig. 1 this flange stops short or terminates near the sides of the tile to provide an open end groove 8 for the reception of the transverse bead 6 at the opposite end of the tile.

Preferably a metal reinforcing rod or bar 9 is placed in the bottom of the channel formed by the grooves 5, beneath the beads 2 of the tile, and cement filling is poured into all the joints of tongue and groove.

The end joints of the lining are staggered as seen in Fig. 1, and the tiles are laid in longitudinal courses as illustrated in the perspective view of the lining, and the elongated reinforcing rods in the channels provided therefor extend a sufficient length to insure a tight locking of the parts and strengthening of the joints as they are embedded in the cement joint.

The tiles are of identical construction, and can thus be made in quantities of production and packed and shipped with convenience,

and facility in handling. And as they are of simple construction and may be laid with perfect fits and adjustment, skilled labor is not required in the building of walls, linings 5 or flumes.

What I claim is—

1. A lining structure composed of courses of longitudinally aligned tiles, the tiles in each course having depending side flanges 10 forming an upwardly extending continuous tongue and a continuous channel, and the tiles in adjacent courses having edge beads forming continuous depending tenons in said channel, and the ends of said tiles having 15 oppositely projecting, transverse, interlock-

ing beads and flanges and grooves located in the side flanges of adjoining tiles.

2. A tile having a longitudinally extending oppositely projecting bead and flange each depending from its outer face and the 20 flange forming an open groove below the face of the tile, an outwardly projecting bead at one end of the tile and an inwardly projecting flange at the other end of the tile forming an end groove below the outer face 25 of the tile, said bead and end flange being shorter than the width of the tile.

In testimony whereof I affix my signature.

AUGUSTUS H. STOWELL.
